NOZZLE VALVE

Application filed October 10, 1929. Serial No. 398,772.

My invention relates to turbines, more particularly to a nozzle block therefor having needle valves movable into and out of the entrances to the nozzles to control the flow of fluid therethrough, and it has for an object to provide an improved construction of the character set forth.

A particular object is to provide mechanism for moving the needle valve to an open position effecting minimum hindrance to and eddying of the motive fluid flowing into the nozzle.

A further object is to provide mechanism for operating the needle valves whereby each valve may be operated at any desired time with respect to the time of operation of said mechanism.

In accordance with my invention, I provide a lever on which the needle valve is carried and which is pivoted on an axis substantially at right angles to the nozzle and spaced therefrom. A rotatable, annular operating ring is provided, and is formed with grooves or slots engaging projections on said levers, whereby, upon rotation of the operating ring, the valves are actuated. By suitably forming or placing each groove, the time of operation of the needle valve controlled thereby may be determined.

The above and other objects are effected by my invention, as will be apparent from the following description and claims taken in connection with the accompanying drawings forming a part of this application, in which:

Fig. 1 is a side elevation of an elastic fluid turbine, with a portion in section showing my novel nozzle block;

Fig. 2 is a plan view of the nozzle valve operating mechanism;

Fig. 3 is a cross-section of said mechanism, being taken on the line III—III of Fig. 4;

Fig. 4 is a side elevation of the same; and,

Fig. 5 is a plan view of a modified form of nozzle valve operating mechanism.

Referring to the drawings more in detail, I show in Fig. 1, a turbine 10 of the bleeder or extraction type, having a high pressure section comprising an impulse stage 11 and a low pressure section comprising an impulse

stage 12 and a number of reaction stages 13. The admission of motive fluid, preferably steam, to the high pressure section is controlled in any suitable manner, as by a valve 14. An extraction opening 15 is provided, through which motive fluid which has been partially expanded in the impulse stage 11 may be extracted for other purposes.

In such a turbine, suitable means is required to regulate the flow of motive fluid to the low pressure section, and I have embodied my invention in the nozzle block 16 of the low pressure section impulse stage 12.

Referring now more particularly to Figs. 2, 3 and 4, the nozzle block 16 has nozzles 17 formed therein for expanding and directing motive fluid against the moving row of impulse blades 18. A needle valve 19 is provided for each nozzle, and it is adapted, when in the position shown in full lines in Fig. 2, to shut off the flow of fluid through the nozzle. The valve 19 is carried on a lever 21, which is pivoted to the nozzle block 16 on an axis extending substantially radially of the turbine, by means of lugs 22 on the nozzle block, a sleeve 23 on the lever and a pivot pin 24 extending through the lugs and the sleeve. The lever 21 is adapted to turn about its pivot and to bring the valve 19 from the closed position shown in full lines in Fig. 2 to the open position shown in dotted lines.

In order to operate the lever 21, it is provided with an arm 25 having a projection 26. An annular operating ring 27 is supported on brackets 28 extending from the nozzle block 16, and it is adapted to be rotated about the axis of the turbine. The ring 27 is provided with a slot 29 for each projection 26, whereby, upon rotation of the ring 27, the sides of the slots 29 contact with the projections 26 to rotate the levers about their pivots.

A spring 31 is provided for each nozzle valve to bias the same to closed position. This is a tension spring having one end connected to a lug 32 on the lever arm 25 and the other end connected to a lug 33 on the ring 27. It will be noted that, as the lugs 32 and 33 move in the same direction upon

rotation of the ring 27, the deflection of the spring is not greatly varied.

As will be noted from the drawings the arms 25, ring 27 and the springs 31 are disposed radially inwardly of the nozzles 19, whereby they do not obstruct the flow of motive fluid to the nozzles.

The operation of the above described embodiment is as follows:

In the position of the ring 27 shown in Fig. 2, all of the valves 19 are in closed position, shutting off the flow of motive fluid through the nozzles 17, by reason of the action of the springs 31 which bias the levers 21 in clockwise direction. It will be noted that the left hand sides of the slots 29 of the first two valves contact with the lugs 26, while the left hand side of the third slot 29 is spaced from the lug 26. Upon rotation of the ring 27 to the right, the first two levers 21 are moved in counter-clockwise direction moving the needle valves 19 out of the mouths of the nozzles 17 to permit flow of motive fluid therethrough. When the ring has travelled an amount equal to the clearance between the left hand side of the third slot 29 and the projection 26, the latter projection is moved to rotate the third lever 21, whereupon the third needle valve 19 is moved to open position.

Upon movement of the ring 27 to the left, the third lever 21 is first rotated to the right by means of the spring 31 until the third valve 19 is brought to closed position, after which the first two valves 19 are moved to closed position as the ring continues to move to the left.

It is thus apparent that the time of opening of any valve with respect to operation of the ring 27 may be determined by the position of the left hand side of the slot 29 in the ring.

In Fig. 5, I show a modified form of my invention, in which grooves 29' are formed in the outer peripheral face of the ring 27'. Projections 26', carried by the levers 21', are disposed in the grooves 29', which are designed to operate the valves at any desired time in the operation of the ring 27' by moving the projections 26' transversely of the ring.

The grooves shown in Fig. 5 are designed to open the valves successively. Each groove consists of a part 34 which holds the valve in open position, a part 35 which moves the valve in opening direction when the ring 27' is rotated to the right and in closing direction when the ring is moved to the left, and a part 36 which holds the valve in closed position. By suitably disposing the part 35 circumferentially of the ring, each valve may be caused to open or close at any desired time in the movement of the ring.

Considering the ring 27' as moving to the right, the projection 26' of the first valve 19' has already passed through the part 35 and the first valve is held open by the part 34.

The second valve is being opened, while the third valve is closed but will begin to open by the time that the second valve has fully opened.

The open or partly open position of the valve 19 or 19' provides a more uniform flow of steam around the valve than in prior constructions. As shown in Figs. 2 and 5, the valve is spaced from the wall of the adjacent nozzle 17 and steam may flow along the path indicated by the numeral A. Steam may also flow above and below the valve as indicated by the path B, and on the hinged side of the valve along the path indicated by the numeral C. The flow of steam into the nozzle is, therefore, substantially uniform around the circumference thereof, producing a smooth flow with minimum eddying.

From the above description, it will be seen that I have provided a novel mechanism for opening and closing a plurality of needle valves adapted to control the flow of motive fluid through the turbine nozzles, said mechanism being capable of effecting movement of each valve at any desired time with respect to the time of operation of the operating mechanism. The novel mechanism also provides minimum hindrance to the flow of motive fluid to the nozzles, and minimum eddying thereof.

While I have shown my invention in but two forms and as applied to an axial flow type of turbine, it will be obvious to those skilled in the art that it is not so limited, but is susceptible of various other changes and modifications, without departing from the spirit thereof, and I desire, therefore, that only such limitations shall be placed thereupon as are imposed by the prior art or as are specifically set forth in the appended claims.

What I claim is:

1. In a fluid pressure turbine, the combination of a plurality of nozzles disposed in a row along a circle concentric with the axis of the turbine, valves pivoted in the turbine and adapted to move to and from the entrances of the nozzles to control the flow of fluid therethrough, and a ring having surfaces engaging parts carried by the valves whereby the ring controls the opening and closing movements of the valves.

2. In an axial flow turbine, the combination of nozzles extending substantially tangentially of the turbine, valves pivoted on axes extending substantially radially and spaced from the mouths of the nozzles, the valves being movable to and from the mouths of the nozzles to control the flow of motive fluid therethrough, and a rotatable ring having surfaces engaging parts carried by the valves for operating the valves, said ring and parts being disposed radially inwardly of the nozzles, providing a substantially unobstructed path for motive fluid in front of the mouths of the nozzles.

3. In a fluid pressure turbine, the combination of a plurality of nozzles disposed in a row along a circle concentric with the axis of the turbine, valves pivoted in the turbine and adapted to move to and from the entrances of the nozzles to control the flow of fluid therethrough, and a ring having surfaces engaging parts carried by the valves whereby the ring controls the opening and closing movements of the valves, said surfaces being so disposed as to cause the valves to be opened and closed successively.

4. In a fluid pressure turbine, the combination of a plurality of nozzles disposed in a row along a circle concentric with the axis of the turbine, valves pivoted in the turbine and adapted to move to and from the entrances of the nozzles to control the flow of fluid therethrough, and a ring having surfaces engaging parts carried by the valves whereby the ring controls the opening and closing movements of the valves, said ring and said parts being disposed to the side of the path of the motive fluid flowing to said nozzles in order to avoid hindrance to the flow of said motive fluid.

5. In an axial flow fluid pressure turbine, the combination of a plurality of nozzles disposed in a row along a circle concentric with the axis of the turbine, valves adapted to control the flow of fluid through the nozzles, said valves being pivoted on axes extending substantially radially of the turbine and having lever arms extending substantially axially of the turbine, and a ring having transverse surfaces engaging said lever arms in valve opening direction for operating the valves.

6. In an axial flow fluid pressure turbine, the combination of a plurality of nozzles disposed in a row concentric with the axis of the turbine, valves adapted to control the flow of fluid through the nozzles, said valves being pivoted on axes extending substantially radially of the turbine and having lever arms extending substantially axially of the turbine, a ring having transverse surfaces engaging said lever arms in valve opening direction, the circumferential spacing of two of the surfaces being different from that of the two valves controlled thereby so that as the ring moves in valve opening direction one surface contacts before the other to provide successive opening of the two valves, and springs biasing the lever arms in valve closing direction against said surfaces.

7. In an axial flow fluid pressure turbine, the combination of a plurality of nozzles disposed in a row along a circle concentric with the axis of the turbine, valves adapted to control the flow of fluid through the nozzles, said valves being pivoted on axes extending substantially radially of the turbine and having lever arms extending substantially axially of the turbine, a ring having transverse surfaces engaging said lever arms in valve opening

direction, the circumferential spacing of two of the surfaces being different from that of the two valves controlled thereby so that as the ring moves in valve opening direction one surface contacts before the other to provide successive opening of the two valves, and springs connected between the ring and the lever arms and biasing the lever arms in valve closing direction against said surfaces.

8. In an axial flow fluid pressure turbine, the combination of a plurality of nozzles disposed in a row along a circle concentric with the axis of the turbine, valves adapted to control the flow of fluid through the nozzles, said valves being pivoted on axes extending substantially radially of the turbine and having lever arms for operating the same, and a cam ring having cam surfaces contacting with said lever arms for moving the valves about their pivotal axes.

In testimony whereof, I have hereunto subscribed by name this 16th day of September, 1929.

FRANK R. SIMPSON.
